UNITED STATES PATENT OFFICE.

THOMAS C. JOHNSON, OF NEW HAVEN, CONNECTICUT, ASSIGNOR TO THE
WINCHESTER REPEATING ARMS COMPANY, OF SAME PLACE.

DESIGN FOR A TEMPORARY CARTRIDGE-CLIP.

SPECIFICATION forming part of Design No. 26,675, dated February 28, 1897.

Application filed September 28, 1896. Serial No. 607,264. Term of patent 14 years.

To all whom it may concern:

Be it known that I, THOMAS C. JOHNSON, of New Haven, in the county of New Haven and State of Connecticut, have invented a new 5 Design for a Temporary Cartridge-Clip; and I do hereby declare the following, when taken in connection with the accompanying drawings and the letters of reference marked thereon, to be a full, clear, and exact description of the same, and which said drawings constitute part of this specification, and represent, in—

15 Figures 1 and 2, outside and inside perspective views of my newly-designed temporary cartridge-clip; Fig. 3, a view of the clip in transverse section on the line *a b* of Fig. 1.

20 My invention relates to a design for temporary cartridge-clips; and it consists in the configuration herein shown and described.

25 My newly-designed temporary cartridge-clip is oblong in general form as to its body portion A, trough-shaped in cross-section, and open at its ends, which are provided with cartridge-retaining devices. The clip is also

formed with an outwardly-projecting ripping-off projection B, standing above the plane of its outer face. As shown, the retaining devices have the form of projecting retaining-fingers C C, which are located on opposite sides of the longitudinal center of the body 30 portion of the clip.

The leading feature of my design is the outwardly-projecting ripping-off projection when present in a temporary cartridge-clip, 35 oblong in general form as to its body portion, trough-shaped in cross-section, and open at its ends, which are provided with cartridge-retaining devices.

I claim—

The design for a temporary cartridge-clip, 40 as herein shown and described.

In testimony whereof I have signed this specification in the presence of two subscribing witnesses.

THOMAS C. JOHNSON.
